US00D804323S

(12) **United States Design Patent** (10) **Patent No.:** **US D804,323 S**
(45) **Date of Patent:** **** Dec. 5, 2017**

(54) **CONTAINER FOR CONTACT LENSES**

(71) Applicant: **CooperVision International Holding Company, LP**, St. Michael (BB)

(72) Inventors: **Glenn Harrison**, Andover (GB); **Gary Hunt**, Bristol (GB); **Matthew Sultan Yan**, Bristol (GB)

(73) Assignee: **CooperVision International Holding Company, LP**, St. Michael (BB)

(**) Term: **15 Years**

(21) Appl. No.: **29/582,505**

(22) Filed: **Oct. 28, 2016**

(51) LOC (10) Cl. **09-03**

(52) U.S. Cl. **D9/756**

(58) **Field of Classification Search**

USPC D9/756, 715-717, 737, 414, 416, 424, D9/425, 430-432; D7/354, 392.1, 394, D7/396.1, 538, 543-545, 550.1, 551, D7/554.3, 587, 566, 575, 584, 619, 629, D7/667, 318, 319, 619.1, 553.6-553.7, D7/554.2; D24/105, 176-180, 227; 224/217; 206/63.5, 553, 557, 541, 775, 206/776, 119, 470, 508, 521.1, 545, 806, 206/217, 820, 5.1; 220/608, 780-806, 220/475, 674, 675, 4.21-4.24, 555, 556, 220/810, 836, 837, 841, 366.1, 367

CPC .. A61C 17/005; A61C 19/006; B65D 43/162; B65D 81/3453

(57) **CLAIM**

The ornamental design for a container for contact lenses, as shown and described.

DESCRIPTION

FIG. 1 is a perspective view as viewed from the front and top direction of the container for contact lenses, showing our new design;

FIG. 2 is a perspective view as viewed from the front and bottom direction thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof;

FIG. 9 is a front cross sectional view thereof, taken along and in the direction of line 9-9 of FIG. 3; and,

FIG. 10 is a front perspective view thereof, shown in an opened position for completeness of illustration.

1 Claim, 6 Drawing Sheets
